UNITED STATES PATENT OFFICE.

LEO M. HARVEY, OF LOS ANGELES, CALIFORNIA.

TIE FOR BOX STRAPS.

Application filed March 14, 1927. Serial No. 175,395.

This invention relates to the construction of a tie for connecting the overlapping ends of flat box bands, such as are employed as "straps" applied around the outside of small 5 boxes and shipping cases, to strengthen them and hold their covers in place.

The general object of the invention is to provide a tie of simple construction which can be readily formed by a machine operating 10 upon the overlapping ends of the flat box band, and which will have a construction which will effectively prevent the overlapping ends from being pulled apart.

It has been attempted heretofore to form 15 a tie between the overlapping ends of flat box bands by bending the overlapping edges of the bands into a plane substantially at right angles to the plane of the flat side of the bands, and in this way forming necks 20 of channel shaped cross-section, with enlargements at the ends of the necks. However, with that form of tie the shoulders at the ends of the necks are necessarily inclined and, when a strain comes upon the band, the 25 shoulder on one band operates in a sense like a wedge to expand the opposite shoulder on the other band.

Further objects of the invention will appear hereinafter.

30 The invention consists in the novel parts and combination of parts to be described hereinafter, all of which contribute to produce an efficient tie for box straps.

A preferred embodiment of the invention 35 is described in the following specification, while the broad scope of the invention is pointed out in the appended claims.

In the drawing:

Figure 1 is a perspective of a box having 40 a box band with a tie embodying my invention.

Figure 2 is a top plan of one of the ties upon an enlarged scale, the body of the band being broken away.

45 Figure 3 is a longitudinal section through the band shown in Figure 2, taken about on the line 3-3' of Figure 2.

Figures 4 and 5 illustrate stages in the process of forming the tie, Figure 4 being 50 a cross-section showing how the ends of the band are superposed on each other preparatory to rolling them into the coaxial rolls shown in Figures 5 and 6. Figure 5 shows a further stage in the process of forming the 55 rolls, and indicates the manner in which the side edges of the overlapping ends of the

band are bent down and around to produce the tubular, or roll form of the tie. In this way, tension on the band at the tie tends to disrupt the tie and cause the overlapping 60 ends of the band to release their grip upon each other. In addition to this, the open channel form of the neck is not adapted to resist the wedging action referred to above, and hence in such a tie the "channels" of 65 the necks tend to flatten out under tension.

One of the objects of this invention is to overcome these objections, and to provide a tie in which the overlapping ends interlock 70 with each other and have such a correlated 75 configuration as will enable the tie to effectively resist relatively great tensile forces without releasing.

In the preferred embodiment of the invention the tie involves the use of two coaxial rolls, which are formed simultaneously. These rolls are of substantially tubular form, with the edges of the two rolls lying on the same side of their axes. One of the objects of my invention is to provide improved means for preventing these rolls 80 from opening up, and in order to accomplish this I provide offsets in the superposed walls of the coaxial rolls on the side of the axis opposite to the edges of the metal. In other 85 words, one of the objects of my invention is to provide a configuration and offsets in the superposed walls of the rolls in such a way as to stiffen the rolls and prevent them from opening, and at the same time to form interlocking shoulders which will not tend, under 90 tension in the band, to expand the tie and disrupt it.

Figure 6 is a cross-section taken about on the line 6-6 of Figure 3, and illustrates 95 the typical cross-section of the tie.

In producing a tie for flat box bands embodying my invention, the overlapping ends of the flat bands are formed into two rolls with the edges of the bands disposed adjacent to each other on the same side of the axis of the rolls, the walls of the rolls on the side of the axis opposite to the said edges having offset portions that operate to stiffen the rolls to prevent the same from opening 100 and which also form a plurality of interlocking shoulders on the rolls to prevent longitudinal movement of either of the rolls with respect to the other.

In the drawing, 1 represents a box provided with a box band 2, shown with a tie 3, embodying my invention. This tie 3 is 110

- shown in detail in Figures 2, 3 and 6. The tie consists of two coaxial rolls 4 and 5, the former of which is produced on the end 6 of the band, and the latter of which is formed on the end 7 of the band. In forming these coaxial rolls, the ends of the band are overlapped together, as illustrated in Figure 4, and the machine which forms the tie, bends the flat ends around, first into substantially the shape illustrated in Figure 5, and afterwards into the form shown in Figure 6. As the flat ends are bent around in this way, of course, the end 6 which is to form the inner roll 4 will be bent to a roll of smaller diameter than the outer roll 5, and hence when the rolling operation is completed the edges 8 of the inner roll 4 will overlap each other in some such manner as that indicated in Figure 6. If desired, the edges 9 of the outer roll may abut each other or slightly overlap. However, the rolls are formed with the edges 8 and 9 lying adjacent to each other and on the same side of the longitudinal axis of the rolls.
- 25 In order to stiffen these rolls and prevent them from opening up when the tie is subjected to tensile strains, at the point 10 diametrically opposite to the edges 8 and 9 with respect to the axis of the tie, I provide offset portions in the walls, and these offset portions not only stiffen the rolls and prevent their opening, but also produce the interlocking shoulders which I rely upon to prevent one of the rolls from slipping on the other under tension.
- In order to accomplish this, the two coaxial rolls are formed by bending the metal around as indicated in Figure 5. I offset the upper sides of the rolls. In doing this, 40 I prefer to form a plurality of offset portions 11 in the rolls on one side of the vertical plane passing through the tie as viewed in Figure 6, and I form a plurality of similar offset portions 12 in the walls of the rolls 45 on the other side of the vertical plane passing through the tie as viewed in Figure 6. The offset portions 12 are intermediate with respect to the offset portions 11, so that an alternating or corrugated effect is 50 produced in the appearance of the tie, resulting in the formation of a plurality of necks 13. The offset portions 11 and 12 may be formed by dies, and they may have substantially straight or inclined faces 14, which 55 are disposed at an angle to each other, the planes of the inclined faces 14 intersecting each other substantially on the vertical axis of the cross-section of the tie (see Figure 6). By reason of these offset portions, a plurality 60 of shoulders 15 are formed in the outer roll 5 and a plurality of similar offset shoulders 16 are formed in the inner roll. These shoulders, being produced at the same time in the machine, are closely adjacent to 65 each other and interlock with each other so

as to prevent any longitudinal movement of one of the rolls with respect to the other.

An examination of the cross-section shown in Figure 6 will indicate one of the reasons why the offset portions operate to stiffen the rolls and prevent their opening up. In this connection it will be observed that, where the inclined faces 14 meet the circular contour of the body of the rolls, angles such as the angle 17 are formed. These angles give stiffness to the material and enable it to resist movements tending to open the angle and spread the overlapping edges 8, 8, or 9, 9, apart.

It is understood that the embodiment of the invention described herein is only one of the many embodiments this invention may take, and I do not wish to be limited in the practice of the invention, nor in the claims, to the particular embodiment set forth.

What I claim is:

1. A tie for connecting the overlapping ends of flat box bands, consisting of two coaxial rolls with the edges of bands disposed adjacent to each other on the same side of the axis of the rolls, the walls of said rolls on the side of the axis opposite to the said edges having offset portions operating to stiffen the rolls to prevent the same from opening, and forming a plurality of shoulders on the rolls interlocking with each other to prevent longitudinal movement of one roll with respect to the other.

2. A tie for connecting the overlapping ends of flat box bands, consisting of two coaxial rolls with the edges of inner roll overlapping each other circumferentially, and with the edges of the outer roll disposed adjacent to the overlapped edges of the inner roll on the same side of the axis of the rolls, the walls of said rolls on the side of the axis opposite to the said edges having offset portions operating to stiffen the rolls to prevent the same from opening and forming a plurality of shoulders on the rolls interlocking with each other to prevent longitudinal movement of one roll with respect to the other.

3. A tie for connecting the overlapping ends of a box band, consisting of two coaxial rolls, the walls of said rolls having inwardly offset portions at a plurality of points along their length forming a plurality of shoulders interlocking with each other to prevent relative longitudinal movement of said rolls.

4. A tie for connecting the overlapping ends of a box band, consisting of two coaxial rolls, the walls of said rolls having a plurality of inwardly offset portions on one side along their length, and having a plurality of inwardly offset portions at points along their length on the other side, the offset portions on one side being disposed between the offset portions of the other side.

and forming a plurality of shoulders on said rolls interlocking with each other.

5. A tie for connecting the overlapping ends of a box band, consisting of two coaxial rolls formed from the overlapping flat ends of the box band with the edges of the bands disposed adjacent to each other on the same side of the axis of the rolls, the walls of said rolls having inwardly offset portions at a plurality of points along their length on the opposite side of the axis of the rolls, operating to prevent the rolls from opening, and forming a plurality of shoulders on the rolls, interlocking with each other, to prevent longitudinal movement of one roll with respect to the other.

6. A tie for connecting the overlapping ends of a box band, consisting of two co-

axial rolls, the walls of said rolls having inwardly offset portions at a plurality of intermediate points along their length forming a plurality of shoulders interlocking with each other to prevent relative longitudinal movement of said rolls.

7. A tie for connecting the overlapping ends of a box band, consisting of a single roll composed of two coaxial rolls, the walls of said rolls having inwardly offset portions at a plurality of intermediate points along their length forming a plurality of shoulders interlocking with each other to prevent relative longitudinal movement of said rolls.

Signed this 7 day of March, 1927.

LEO M. HARVEY.
